UNITED STATES PATENT OFFICE

144,675

DESIGN FOR AN AMPHIBIAN AIRPLANE

Lois F. Beard, St. Petersburg, Fla.

Application February 1, 1945, Serial No. 117,700

Term of patent 14 years

(Cl. D71—1)

To all whom it may concern:

Be it known that I, Lois F. Beard, a citizen of the United States, residing at St. Petersburg, in the county of Pinellas and State of Florida, have invented a new, original, and ornamental Design for an Amphibian Airplane, of which the following is a specification, reference being had to the accompanying drawings, forming part thereof.

Figure 1 is a top plan view of an amphibian airplane embodying my new design. Fig. 2 is a

side elevational view thereof, Fig. 3 is a front elevational view thereof, and Fig. 4 is a rear perspective view thereof.

The dominant features of my design are shown by means of full lines in the drawings.

I claim:

The ornamental design for an amphibian airplane, as shown and described.

LOIS F. BEARD.
